UNITED STATES PATENT OFFICE.

EDWIN R. GILL, OF ENGLEWOOD, NEW JERSEY, ASSIGNOR, BY MESNE ASSIGNMENTS, TO ELECTRITE COMPANY, A CORPORATION OF NEW YORK.

MEANS FOR CONTROLLING ELECTRIC OR OTHER MOTORS.

SPECIFICATION forming part of Letters Patent No. 694,369, dated March 4, 1902.

Application filed July 26, 1898. Serial No. 686,869. (No model.)

To all whom it may concern:

Be it known that I, EDWIN R. GILL, a citizen of the United States, residing in Englewood, in the county of Bergen and State of New Jersey, have invented a certain new and useful Improvement in Means for Controlling Electric or other Motors, of which the following is a specification.

My present invention has relation to means whereby the main controllers of electric cars may be operated singly or in groups from a single master-switch.

It is the main object of my invention to provide means whereby a solenoid may be applied to the usual drum-controllers on electric cars in such a manner as to allow of step-by-step movement in either direction on appropriate use of a master switch or manipulator at any point on a car or train of cars.

Another object of my invention is to provide a device of the class described which shall automatically turn the drum controller or controllers back to off position for all the car-motors whenever current-supply fails, whether by accident at the power-house or from another cause.

My invention is illustrated in a preferred form in the accompanying drawings, where-

30 in—
Figure 1 is a diagram of the principal elements of my preferred device and operating-circuits. Fig. 2 is a diagram of the details of one of the selector devices employed in my 35 device. Fig. 3 is a section on the line *a b*, showing my preferred solenoid core and rack. Fig. 4 illustrates the motive mechanism in section on the top of a well-known controller-box for electric cars. Fig. 5 is a plan view 40 of the magnetic locking-valve, and Fig. 6 is a sectional view of the same.

The top of a controller-box is shown at 1 in Fig. 4, and the usual rotating shaft at 2. To the end of this shaft I fix a gear-wheel 3, 45 and surrounding the shaft and fastened to it is a spiral spring 4, tending always to bring the shaft 2 to the position corresponding to stoppage of the motors to be controlled. A straight rack 5 meshes with the gear 3, (see 50 Fig. 4,) as shown in Figs. 3 and 4. This rack is preferably set into the side of a magnetic

core 6, which is adapted to slide back and forth within the solenoid 7 in a well-known manner. The coils of the solenoid 7 are indicated in Fig. 1 in two sections. The forward section 8 is shown in heavy dotted lines, and the rear section 9 is shown in lighter dotted lines. The section 8 is the active section, whose tendency is to pull the rack 5 inward, thus acting through the gear 3 to oppose the returning-spring 4 and admit current in the usual manner to the motors. The windings 9 are opposed in magnetic effect to windings 8 and are of higher specific resistance, as indicated by the lighter dotted lines. When the two coils 65 are in series, they have the same ampere-turns, but as they oppose each other their resultant magnetic effect is *nil*. The coil 9 is made of high resistance in order to reduce the continually-applied current to a minimum. 70

On the end of the solenoid-core 6 there is a cross-bar 10, carrying on its upper end two insulated contact-fingers 11 12 and on its lower end a piston-rod 13. The piston 14 on the end of the rod 12 plays within an appropriate cylinder 15. This cylinder is filled with an appropriate fluid, and the spaces on the two sides of the piston 14 are in communication through the pipe or passage 16.

The cone-valve 17 is held down to an adjustable screw-pin abutment 18 by fluid-pressure existing when the piston 14 moves inward, (or toward the right in Fig. 1;) but pressure in the opposite direction effects the opening of said valve in a well-known manner. It will 85 thus be seen that the piston 14 is free to move outward (or to the left in Fig. 1) at full speed, while an adjustably-slow movement is alone permitted in the opposite direction. Since the piston 14 and its rod 13 are attached to 90 the cross-head 10 on the operating-solenoid core, it is clear that my device makes it impossible to turn current on through controller 1 faster than a predetermined speed, while the return to a stopping position may be effected as quickly as desired. At another point in the by-pass 16 I provide a rotating valve or tap 19, having an opening 20, directed as shown in Fig. 1. This passage will complete the free passage through 16 when actuated 105 by the spiral spring 21, which tends to keep it open. (See Fig. 6.) This spring is attached

to the stem above the tap 19. Above the spring 21 there lies an armature 22, governed by the field-magnet 23, whose poles are shown at 24 25. The spring 21 in opening the valve 19 throws the armature 22 into the position shown in dotted lines in Fig. 5; but when the magnet is energized it assumes the full-line position, thus closing the valve, as shown in Fig. 1. It is obvious that when the magnet 23 is energized and the valve 19 closed the fluid is unable to pass from one end of the cylinder 15 to the other, and the piston 14 is thus locked in place, and with it the solenoid-core, the gear 3, and the controller-shaft 2.

15 When the controller is in the "off" position, current passes by wire 26 to coil 8 and 9 in series, thence by wire 27 to magnet 23, wire 28, through coils of magnet 29, and out at 30. The magnet 29 acts to support an armature 31, which when it drops closes a short circuit around the high-resistance coil 9 at 32. In order to operate these devices from a distance in a single group or several groups at a time, I provide a master-switch having a lever 33, moving over the desired number of contact-points *a b c d*, corresponding to the desired stopping positions of the controller. Each contact *a, b, c*, and *d* is in permanent electrical connection with a corresponding fixed contact-piece *a', b', c',* and *d'* upon the solenoid 7, and over these latter contact-pieces the fingers 11 and 12 are made to move whenever the core 6 moves. Dead-blocks are placed one at each end of the row of contacts *a', b', c',* and *d'*, as shown in Figs. 1 and 2. The finger 12 being shorter than the finger 11, when the latter rests upon any given block 12 will touch the block to the left of it in Figs. 1 and 2.

40 Coöoperating with the metallic lever 33 are two frictional selectors. These consist of the levers 34 and 35, each split at the butt and embracing the pivotal shaft of the lever 33, so as to tend to always turn with it. Owing 45 to the frictional nature of the connection, however, when a stop is placed in the path of either selector-lever 34 or 35 the lever 33 may still move onward at the mere expense of friction. On each side of the tip of each lever 50 34 35 is a terminal stop, placed so near to the median position of each lever that a slight movement of the main lever 33 suffices to break connection with one stop and establish contact with its opposite. The stops for lever 55 34 are shown, respectively, at 36 and 37, and the stops for lever 35 are shown at 38 and 39. It will be observed that whereas the lever 34 is made in a single conducting piece the lever 35 is made in two parts, separated electrically at 40. By this arrangement current entering the tip of lever 34 will pass directly to lever 33, while current admitted to the tip of lever 35 will pass only to wire 41, leading to magnet 29, as shown in Fig. 1.

60 65 The operation of my device is as follows: The controller being at the "off" position and being locked there by the magnet 23, which

is energized by the constant current also passing through the mutually-opposing solenoid-windings 8 and 9 and through the magnet 29, 70 it is desired to turn the controller to admit current to the main motors. The lever 33 is turned to the right in Fig. 1 until it touches at *a*. This brings levers 34 and 35, respectively, in contact with 36 and 38, and the circuit established is as follows: entering at 26 through both coils 8 and 9, wire 27, magnet 23, wire 28, wire 41, stop 38, finger 11, contacts *a'* and *a*, lever 33, lever 34, stop 36, wire 42, and out at 30. A short circuit is thus thrown around the magnet 29 and armature 31 drops, closing a short circuit at 32 around both the magnet 23 and the high-resistance coil 9. This circuit enters at 26, goes through coil 8, thence by wire 43 to points 32, by wire 41, stop 38, finger 11, contacts *a'* and *a*, levers 33 and 34, stop 36, wire 42, and out at 30. The magnet 23 being short-circuited, the valve opens, and the unopposed coil 8 acts upon the solenoid-core to turn the controller to its first 80 starting position. The fingers 11 and 12 move with the core 6 until the short circuit around magnet 29, above described, is broken at *a'* and finger 11 rests on *b'*. The armature 31 is at once raised and the short circuit at 32 is 85 broken. Magnet 23 is again energized, locking the controller in position by closing valve 19, and the coil 9 again comes into circuit to nullify the action of coil 8. If the lever 36 be moved to any point farther to the right, the controller will be moved to a corresponding position by operations similar to that above described until at last the finger 12 rests upon the contact *d'* and finger 11 on the dead-block next it. This corresponds to full speed of the 90 controlled motors. If now the lever 33 be moved toward the left in Fig. 1, the first small movement will bring levers 34 and 35 in contact with stops 37 and 39, respectively, the tip of lever 33 still touching contact *d*. 95 This will have the effect of short-circuiting the magnet 23 only, as follows: from 26, through both coils 8 and 9, by wire 44 to 37, by levers 34 and 33, contacts *d* and *d'*, finger 12, point 39, wire 41, magnet 29, and out at 100 30. The solenoid will remain neutral; but the valve 19 being opened the spring 4 on the controller-shaft will be free to move it backward toward stopping position. This will move the finger 12 onto *c'* and break the 105 short-circuit at *d'*. The magnet 23 will close valve 19, and the controller will again be locked. This operation can be repeated by reestablishing short-circuit of magnet 23 at 110 *c, b*, and *a*, successively, until stopping position is again reached.

115 It is clear that the operation of returning to stopping position of the controller can be accomplished at any position of the lever 33 by simply tipping this lever backward sufficiently to throw levers 34 and 35 from one stop to the other and then moving the lever to such stop or stops as desired.

120 125 It is clear that if at any time current fails

in the car the effect will be to deenergize the magnet 23, thus unlocking the controller and permitting the spring 4 to return said controller to the off position.

5 The construction above described serves to manipulate one controller or several at once by a single master-switch at any desired point by means of a solenoid acting step by step, as desired.

10 The construction above shown and described may be varied indefinitely by the judgment of those skilled in the art without departing from the scope of my present invention, and I do not limit myself to the precise details herein shown and described.

What I claim is—

1. In a system of electric control, a solenoid for producing increase or decrease of power, a hydraulic cylinder and a piston moving with 20 said solenoid-core, a tube for permitting flow of liquid from end to end of said cylinder around said piston, and an automatic valve in said tube for retarding said flow in one direction while offering no substantial resistance in the opposite direction.

2. In a system of electric control, a power-regulator, a controlling-actuator therefor comprising a solenoid and core, said solenoid having two coils of practically equal opposing 30 magnetic effects, and means for cutting one of said coils out of circuit at will.

3. In a system of electric control, a power-regulator, a controlling-actuator comprising a solenoid and core, said solenoid having two 35 coils of practically equal opposing magnetic effects, a short circuit, as 32, around one of said coils, a magnet for keeping said short circuit open, and means for short-circuiting said magnet at will.

40 4. In a system of electric control, a power-regulator, a controlling-actuator comprising a solenoid and core, said solenoid having two coils of practically equal opposing magnetic effects, a short circuit, as 32, around one of 45 said coils, a magnet for keeping said short circuit open, a winding on said magnet coiled so as to counteract the active coils thereof,

and means for passing current through said counteracting winding.

5. In a system of electric control, a power-regulator, a controlling-actuator comprising a solenoid and core, said solenoid having two coils of practically equal opposing magnetic effects, but one being of higher resistance than the other, and means for cutting said 55 high-resistance solenoid-coil out of circuit at will.

6. In a system of electric control, a solenoid having opposing windings a hydraulic cylinder and piston governing the movements of 60 said solenoid, a valve controlling the liquid flow in said cylinder, a magnet governing said valve, a short circuit around said magnet and one of said opposing coils, and a second magnet governing said short circuit. 65

7. In a system of electric control, an interrupting-switch wherein the movable member has two insulated brushes touching different stationary terminals, two magnets for governing the controlling-actuator, and a manipulator comprising two automatic selectors, as 70 34, 35, for selecting one or the other magnet, and one or the other brush of the interrupting-switch respectively.

8. In an electric car, the combination with 75 the usual barrel switch-controller, of the solenoid-motor and governing-switch for operating the controller, said motor mechanically geared with the controller-shaft, and means for effecting retraction of the solenoid-core to the off position when the current is interrupted.

9. In an electric car, the combination with the usual barrel switch-controller, of the solenoid-motor and governing-switch for operating the controller, said motor mechanically 80 geared with the controller-shaft, and a spring for effecting retraction of the solenoid-core to the off position where the current is interrupted. 85

EDWIN R. GILL.
